UNITED STATES PATENT OFFICE.

GUY W. FERDON, OF CRESSKILL, NEW JERSEY, ASSIGNOR TO SILVER & CO., OF BROOKLYN, NEW YORK, A CORPORATION OF NEW YORK.

DESIGN FOR AN EGG-POACHER.

55,599.

Specification for Design.

Patented July 6, 1920.

Application filed April 27, 1920. Serial No. 377,120. Term of patent 14 years.

To all whom it may concern:

Be it known that I, GUY W. FERDON, a citizen of the United States, residing at Cresskill, in the county of Bergen and State of New Jersey, have invented a new, original, and ornamental Design for an Egg-Poacher, of which the following is a specification, reference being had to accompanying drawing, forming part thereof.

Figure 1 is a top view of an egg poacher, showing my new design.

Fig. 2 is a side view.

Fig. 3 is a bottom view.

I claim:

The ornamental design for an egg poacher, as shown.

GUY W. FERDON.
